UNITED STATES PATENT OFFICE.

JAMES A. NOBLE, OF NEW YORK, N. Y., ASSIGNOR TO E. L. NOBLE, OF BROOKLYN, NEW YORK.

HAND-OPERATED CAR-BRAKE.

1,156,849.

Specification of Letters Patent.

Patented Oct. 12, 1915.

Application filed September 17, 1914. Serial No. 862,133.

To all whom it may concern:

Be it known that I, JAMES ARTHUR NOBLE, a citizen of the United States, and resident of the borough of Brooklyn, county of 5 Kings, city and State of New York, have invented certain new and useful Improvements in Hand-Operated Car-Brakes, of which the following is a specification.

For economy and for ease and rapidity of 10 operation the present tendency is toward a type of brake generally termed a staffless brake, one wherein a rigid or rotatable vertical member or staff upon which the hand-wheel was horizontally supported is omitted 15 to be substituted by a chain or other flexible member received upon a drum or an approximation thereof, which drum is arranged horizontally and supported at a definite height and is operated by a vertically 20 disposed hand-wheel. Of such a type is this my present invention, and although in the construction of my device I have used certain parts well known and well understood, I arrange them in a manner to obtain in a 25 most efficient way all the advantages that may be derived from a staffless brake.

The particular construction and method of operation of my device will be fully set forth as this specification progresses.

30 The following is what I consider the best means of carrying out this invention, and the accompanying drawings form a part of this specification, in which:

Figure 1. is a front elevation. Fig. 2. a 35 side elevation partly in section.

Similar reference numerals indicate like parts in all the figures where they appear.

At 1 I have shown a casing or column which may be formed of cast-iron or other 40 suitable material which is provided with a detachable cap 2 and a base 1'. The cap, column and base are hollow and it is within these parts that the operative portion of my mechanism is arranged.

45 Formed in the column and cap, and arranged about one half in each of these members are a plurality of bearings 3 and 4 and arranged in these bearings is a shaft 5 which may be rotated therein or it may be secured 50 within the bearings. I arrange a compound sheave having a large portion 6 and a smaller portion 7 secured together or formed integral. Both parts of this sheave are supplied with a groove, and a sufficient groove 55 arranged on an incline connects the two

grooves of the parts 6 and 7. Across the grooves 6 I arrange a pin 8 to which the brake chain will be secured and a rotation of the sheave will cause the chain to be taken or to be wound into the grooves 6 60 and 7.

To rotate the compound sheave I provide an internal gear 9 secured to the sheave or cast integral therewith, and within this gear 9 I arrange a pinion 10 in mesh with the gear 65 and supported upon a rotatable shaft 11 which is in turn mounted in a broad bearing 12 which projects from the cap 2. A hand-wheel 13 is secured upon the shaft 11 exterior to the cap 2 and serves as a means 70 whereby the pinion 10 and gear 9 may be rotated for the purpose of imparting motion to the compound sheave. Exterior to the gear 9 I arrange a ratchet 14, this ratchet may also be cast integral with the gear 9 75 and the compound sheave, and I provide a dog 15 pivoted at 16 into the column 1 for checking the motion of the ratchet 14 and the parts rotatable therewith. A bar 20 extends downward through the column 1 and 80 has its upper end secured to the dog 15. The lower end of the rod 20 is pivotally engaged with the foot pedal 17.

It will be noted that the enlarged portion 15' of the dog 15 tends to hold the dog out 85 of engagement with the ratchet 14. Engagement of the dog with the ratchet is accomplished either by the depression of the foot lever 17 or by means which will now be described.

90 It is desirable in all chain brakes that the chain shall not unwind to a great extent and to prevent this I secure a second chain 18 to the operating end of the dog 15, the other end of the chain 18 is secured to the brake 95 operating chain and I take care to provide only a sufficient length of chain 18 that will allow the brake chain to run out to a sufficient length to free the brake. A further movement of the brake chain will cause the 100 dog 15 to engage the ratchet which will prevent further unwinding of the brake chain.

105 It will be noted that I provide a compound sheave or rather one having a spiral chain groove, the larger end of the groove will take up the slack quickly, and the smaller end will exert a power upon the brake chain. From this construction I provide not only a rapidly operating brake but one that will be found to contain a means 110

for operating effectively and with sufficient force.

Modifications may be made within the scope of the appended claims without departing from the principle or sacrificing the advantages of this invention.

Having carefully and fully described my invention, what I claim and desire to secure by Letters Patent is:

- 10 1. A brake having an internal and external gear and a sheave, a chain operable therewith, a ratchet and dog operable with said gears, and means for operating said dog by the motion of said chain, as and for the purpose set forth.
- 15 2. A hand operated car brake provided with a flexible member; a sheave having a spiral groove, means for rotating said sheave, a ratchet formed integral with said

sheave, a dog operable therewith, and an automatically operated means operated by the movement of said flexible member for operating said dog, as and for the purpose set forth.

3. A hand operated car brake having a 25 sheave with a spiral groove, means for rotating said sheave, a ratchet formed integral with said sheave, a dog operable therewith, and a manually and automatically operated means for operating said dog, as and for 30 the purpose set forth.

Signed at New York city, in the county and State of New York this 28th day of Aug. 1914.

J. A. NOBLE.
